UNITED STATES PATENT OFFICE.

ARTHUR LEWRAY HEWITT, OF BOYNE FALLS, MICHIGAN.

MANURE-SPREADER.

1,251,372.

Specification of Letters Patent. Patented Dec. 25, 1917.

Application filed May 5, 1917. Serial No. 168,633.

To all whom it may concern:

Be it known that I, ARTHUR L. HEWITT, a citizen of the United States, residing at Boyne Falls, in the county of Charlevoix 5 and State of Michigan, have invented certain new and useful Improvements in Manure-Spreaders; and I do hereby declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to new and useful improvements in agricultural machinery, and particularly to machinery known as manure spreaders.

20 The important feature of the invention resides in the provision of a device of this character adapted to be employed with the usual wagon frame now in use.

A further object is to provide a movable 25 bottom and means independent of the wheels of the wagon to which this device is applied for operating the movable bottom.

A still further object is the provision of 30 means for automatically throwing the operating means into and out of operation.

The invention comprises various details 35 of construction, combinations and arrangements of parts which will be hereinafter fully described, shown in the accompanying drawings and then specifically defined in the appended claim.

I illustrate my invention in the accompanying drawings, in which:—

Figure 1 is a plan view of the invention.

40 Fig. 2 is a longitudinal view of the device taken on line 2—2 of Fig. 1.

Fig. 3 is a rear elevation.

Fig. 4 is a transverse sectional view.

45 Fig. 5 is an enlarged plan view of the clutch mechanism.

Fig. 6 is an enlarged detail view of the clutch mechanism.

Reference now being had to the details of 50 the drawings by numeral, 1 indicates the side boards of the body of the manure spreader, the lower ends of which are connected to the skeleton frame comprising side rails 2, to which are connected the cross bars 3. Supported in spaced relation with the side 55 rails 2 and disposed on the inner sides of

the side boards 1 are the supporting rails 4 and 4', forming the track for the movable bottom 5, comprising a plurality of connected sections 6 and a head board 7 through which extends an eye bolt 8 to which is 60 connected one end of the flexible connecting member 9, the opposite end thereof having connection with the opposite end of the flexible bottom as at 10, the intermediate portion of the flexible member 9 passing 65 over the pulley 11, slidably mounted on shaft 12' and comprising sleeves 12^a and 13' having clutch faces 12 and 13 at the respective ends thereof. Supported in spaced relation with the shaft 12' is a drive shaft 70 14 having sprocket wheel 15 keyed or otherwise secured thereto, adjacent one end thereof, while a similar sprocket 16 is keyed adjacent the opposite end thereof. The sprocket wheel 16 has communication with 75 the sprocket wheel 17 which in turn is rigidly secured to the shaft 12' through chain 17', said sprocket wheel also having clutch face 18 adapted to coöperate with the clutch face 13 of the sleeve 13' for communicating 80 motion thereto. A clutch face 19 is also keyed to the shaft 14 and coöperates with clutch face 20 formed on the slidable sleeve 21, said sleeve carrying a sprocket wheel 22 having communication with the engine 23 85 by suitable means, not shown, and it will be seen that, when the lever 24 is moved in one direction, clutch faces 19 and 20 are brought into engagement with each other with the result that the shaft 14 is brought 90 into operation.

At the opposite end of the shaft 12' is a sleeve 25 having clutch face 26 and carrying a sprocket 27, having communication with the sprocket wheel 15 through chain 28. 95 Pivotally supported on the frame is an operating lever 29 having a forked end 30, engaging the flange 31 on the sleeve 12^a, the opposite end of the lever 29 being pivotally connected to the lug 32 formed on the sliding arm 33, operating through guides 34 secured to one of the side bars 4, one end of said arm 33 extending upwardly and forming an abutment to be engaged by one end of the bottom 5 for operating the sleeve 12^a 105 and consequently throwing the clutch faces 12 and 26 out of operative relation.

On the opposite side of the body is a sliding arm 35, supported on the side rail 4', having connection with lever 36 which 110

is connected to sleeve 13', for moving the clutch faces 13 and 17 out of operation. The end 37 of arm 35 extends upwardly to engage the other end of the movable bottom 5 5 for automatically operating the sleeve 13'.

A lever 38 is pivoted to the frame of the body, the lower end thereof being connected with the collar 39 and it will be seen that, by movement of said lever 38, the clutch 10 faces may be moved into co-operative relation with each other, for setting the machine in operation.

In operation, the bottom 5 having been moved to the position indicated by Fig. 7, 15 the engine is started and clutch faces 19 and 20 brought into co-operative relation with each other. The shaft 14 is accordingly rotated with the result that rotary movement is transmitted to the drum 11 and the bottom 20 is moved in the direction of the arrow in Fig. 4, the load being distributed, and the rear end of the bottom 5 is moved forward and engages lever 38, with the result that the clutch members 12 and 26 are moved out 25 of engagement and serving to stop the movement of the bottom in one direction. In order that the bottom 5 may be returned to its normal position, the clutch faces 13 and 17 are moved into operative relation with the 30 result that the bottom is moved to the position shown in Fig. 6 and it follows that, when the forward end of the bottom reaches its limit, the same engages the lever 35 and clutch faces 13 and 17 are disconnected and

the movement imparted to the drum will be 35 reversed.

What I claim to be new is:—

A manure spreader comprising a frame, a flexible bottom, rollers over which the floor travels, a driving shaft, sprocket wheels fixed thereto, a second rotatable shaft, sprocket wheels journaled thereon and each having clutch teeth at their inner ends, sprocket chain connections between the wheels upon the two shafts, a drum splined to said second 40 referred to shaft and having clutch teeth upon projecting ends thereof, a cable fastened to the ends of the flexible floor and winding about said drum, a pivotal clutch throwing lever, a collar swiveled to the drum 45 and pivoted to said lever, pivoted angled levers having fork ends engaging annular grooves formed in projecting portions of the drum, sliding bars pivotally connected to said angled levers and having bent portions 50 so positioned that the ends of the flexible floor will contact therewith when moving in opposite directions, whereby the drum may be moved longitudinally to engage or disengage the clutch teeth on said sprocket 55 wheels, as set forth.

In testimony whereof I hereunto affix my signature in presence of two witnesses.

ARTHUR LEWRAY HEWITT.

Witnesses:

GEO. L. OLSEN,
HARRY C. DE NISE.
